E. M. Mandel

UNITED STATES PATENT OFFICE

HYMAN GOLDFINGER, OF BROOKLYN, NEW YORK

WINDOW SHADE BRACKET

Application filed March 29, 1929. Serial No. 350,859.

This invention relates to improvements in shade brackets, and more particularly to a bracket which will be so formed that when mounted on the sides of an upper sash, the same may be swung out of position or detached so that the upper and lower sashes may pass each other without engaging any obstruction.

10 *Objects*

An object of the invention is to provide an improved shade bracket which will be supported upon the upper sash of a window, and so arranged that it may be bodily swung to extend parallel with said sash, or removed when it is desired to slide one sash past the other.

Another object of the invention is to provide an improved shade bracket with means whereby the same may be detachably secured to a window sash, and with means for securing a shade roller in the bracket when positioned therein.

Other objects will appear as the description proceeds.

25 *Drawings*

In the accompanying drawings which form a part of my application,

30 Figure 1 is a front elevation of a portion of window frame and sashes, showing the positioning of my improved shade hanger;

Figure 2 is a sectional view taken on the line 2—2 of Figure 1;

35 Figure 3 is a perspective group view of the shade hanger.

Like characters of reference are used throughout the following specification and the accompanying drawings to designate corresponding parts.

40 *Description*

In the drawings, I have illustrated the usual form of window frame 1, and upper sash 2 and lower sash 3, slideable within said frame.

It has heretofore been necessary to mount the shade and shade brackets at the sides of the window frame 1, above the sashes, but I have devised an improved and efficient form

of shade hanger which may be mounted on the side pieces of the sashes, and may be removed bodily, or swung out of the way, when it is desired to slide one sash by the other.

I have provided a U-shape supporting member 4, having laterally extending fastening wings 5, which in turn are provided with openings 6, through which fastening screws may be placed. The bottom or intermediate portion of the member 4 extends parallel with the fastening wings 5, but lies in a plane spaced from the plane of said wings. A locking slot 7 is formed in the member 4, extending approximately half the depth of said member, and in the connecting portion between said intermediate portion and a fastening wing.

The shade hanger proper comprises a base member 8 having a slot 9 formed therein and adapted to be received within the supporting member 4, behind the bottom portion thereof, with the slots 7 and 9 cooperating with each other. The hanger is bent forwardly at right angles to the base 8 and is provided with the usual notch 10 adjacent its free end to receive the pintle of a shade roller. A latch 11, of substantially U-shape in cross section is pivoted to the forwardly extending portion of the hanger and is adapted to lock down over the notch 10 to retain the roller in fixed position therein, while a tab 12 extends outwardly from the free end thereof to enable one to grip the latch to manipulate the same.

Many minor changes in detail of construction may be resorted to without departure from the spirit of the invention.

Having thus described my invention what I claim as new and desire to secure by Letters Patent of the United States is:

A shade bracket as characterized comprising a member adapted to be fixed to a window sash or the like and a member adapted to be removably supported by the fixed member, said removable member having a flat base portion and an outstanding hanger portion, said fixed member having side flanges in a common plane and an intermediate portion offset from the plane of said flanges by offsetting portions substantially the thickness

of the material comprising the removable member, one of said offsetting portions having its upper part cut away for providing a downwardly-extending slot at one side edge of the offset portion between the offset portion and one of the flanges, whereby the flat base portion of the removable member may extend straight through the slot partly beyond the offset portion and partly in front of the flange in flatwise engagement with both the offset portion and the flange, said base portion having an upwardly-extending slot to receive the lower part of the offsetting portion of the fixed member below the downwardly-extending slot of said fixed member and having a width from the upwardly-extending slot to the free end of the base portion substantially the width of the offset portion, whereby the fixed member and removable member may be of substantially the same height and the removable member will be retained against twisting in any direction.

HYMAN GOLDFINGER.
